UNITED STATES PATENT OFFICE.

JOHN J. SPROUL, OF NEW YORK, N. Y., ASSIGNEE OF ONE-HALF TO AUGUST SUNDH, OF HASTINGS-UPON-HUDSON, NEW YORK.

ELEVATOR.

1,218,711.

Specification of Letters Patent.

Patented Mar. 13, 1917.

Application filed May 1, 1916. Serial No. 94,576.

To all whom it may concern:

Be it known that I, JOHN J. SPROUL, a citizen of the United States, and resident of New York, in the county of New York 5 and State of New York, have invented a certain new and useful Elevator, of which the following is a specification.

My invention relates to elevators of the type in which a motor operated by non-compressible fluid is employed to drive the elevator car, and more particularly the invention involves a motor driven by oil or other non-compressible fluid under steam pressure. Preferably, a reciprocating motor 10 is connected to and arranged to rotate a drum for driving the elevator car by means of hoisting cables. The steam which applies pressure to the non-compressible fluid may be derived directly from a steam generating plant in the building, or from an 15 outside source of steam supply.

An object of the invention is to provide an elevator particularly adapted for high buildings and which will have a high efficiency, and which will be simple, safe and practical for driving the elevator by steam pressure applied directly to non-compressible fluid which drives the motor for lifting the car. The arrangement dispenses with 20 the power transforming elements including engines, electric generators, and electric motors, or pumps, usually interposed between the steam generator and the motor for driving the elevator car, as in hydraulic elevators, wherein a steam pump is employed 25 for returning the fluid to the pressure tank, or as in electric elevators, wherein a steam engine and an electric generator are employed for generating current for the motor which drives the elevator, each of which 30 elements transforms the power at a great loss of efficiency.

The invention also secures the advantages of an overhead motor connected directly to 45 the hoisting drum and adapted to rotate the same, and provides for the use of a motor which is comparatively small, compact and light in weight, and therefore well adapted for overhead use.

During the travel of the elevator car from 50 the bottom to the top of its run, or vice versa, the motor makes a certain number of revolutions, and a corresponding amount of the non-compressible fluid which actuates the

motor, is circulated therethrough from the 55 pressure tank to the discharge tank or vice versa. It is important that a sufficient quantity of the fluid be supplied to last for at least one trip of the car in either direction, so that there will always be a supply of the 60 fluid to the motor. If the supply of non-compressible fluid should run short, the control of the car and motor would be lost.

I use lubricating fluid or oil to be circulated through and actuate the engine because it lubricates the engine, packings can be dispensed with in the engine, and the efficiency is greater and the life of the engine longer than when water is used therein. I employ a column of water however 70 between the steam and oil to avoid heating of the oil and also to prevent oil from being drawn back with the water condensed from the steam, to the steam boiler.

I am familiar with, and have had experience in installing and operating elevator systems known as hydro-steam elevators, in which a piston or a plunger is operated in a cylinder and driven by fluid controlled by steam in a pressure tank. The present invention is an improvement on such systems, because it can be used to great advantage in very high buildings, since a rotary element is employed to drive the elevator. As the steam is conducted from the generating 80 plant in the cellar to the top of the building with very little loss of efficiency, the elevator engine for driving the rotary element may be placed at the top of the building, no matter how high the building is. Also, 85 because the size of the engine does not need to be increased in proportion to the height of the building, the present system can be used where it would not be possible to use the old style or hydro-steam elevator. 90

In the present system, I prefer to have the cables on the drum free and operated by frictional contact with the drum. This is an advantage in that the drum does not need to be so large as would be required if 100 the cables were fastened to the drum. I prefer to use a multiple cylinder engine, although some other rotary engine might be used. A multiple cylinder engine has a large factor of safety, as each cylinder forms 105 a safety device, and there is hardly a possibility of all the cylinders breaking at one time. Also the multiple cylinder engine is

well adapted to operate as a pump while the elevator car is descending, so that it operates as a safety device and controller during both the ascent and descent of the car.

5 In practising the invention, the elevator car may be driven by an overhead motor of the type above mentioned, which is connected directly to a hoisting sheave to drive the car by means of cables running from the 10 car over the sheave and connected to counterweights. Steam under pressure may be supplied from a generator in the basement of the building or other convenient location, the steam being conveyed to an overhead 15 tank to supply pressure to water therein. Said tank communicates with a second pressure tank containing oil or the like for driving the motor. The steam pressure when admitted to the water tank is transmitted 20 through the water to the oil pressure tank, forcing the oil therein through the rotary motor to drive the same. The oil which circulates through the motor is conducted therefrom to a reservoir which may be open 25 to atmospheric pressure. The motor is driven by the oil in a direction to lift the car.

The car may be lowered by its own weight, the motor being driven thereby in the 30 reverse direction, and acting as a pump to circulate the oil through the motor in the reverse direction, whereby the oil is returned to the pressure tank. A friction brake may be connected to the motor shaft and may be 35 operated to a released position by steam pressure. The supply of steam pressure to the water pressure tank, the circulation of the oil through the motor, and the supply of steam to the brake, may be controlled by 40 magnetically operated valves electrically controlled from the car.

Other features and advantages of the invention will appear hereinafter.

Referring to the accompanying drawings 45 which illustrate an elevator system embodying the principles of my invention, Figure 1 is a part sectional elevation showing the elevator as installed in a building. Fig. 2 is a front sectional elevation of the motor. Fig. 3 is a sectional side elevation of the same. Fig. 4 is a part sectional elevation of the brake and operating means therefor. Fig. 5 is an elevation view of the water pressure tank, the valve controlling the supply of steam pressure thereto, and the electromagnets for operating the valve, the valve being shown in section. Fig. 6 is a diagrammatic view of the electric circuits and the various controlling magnets. Fig. 7 is a sectional plan 55 view of the set of valves controlling the circulation of liquid through the motor, the view being taken at the section line 7-7, on Fig. 9. Fig. 8 is a part sectional elevation of the same, the section being at the line 8-8 60 on Fig. 9. Fig. 9 is an elevation of the same

looking in a direction at right angles to that of Fig. 8. Fig. 10 is a sectional elevation at the line 10-10, of Fig. 7.

Referring particularly to Fig. 1, the elevator car A is driven by a motor B, having a 70 shaft 11 on which is mounted a hoisting sheave 12, over which run hoisting cables 13, connected at one end to the car and at the other end to a counterweight 14. The car and counterweight travel between vertical 75 guide rails 15 and 16 respectively. A friction brake C may be mounted directly on the drive shaft 11. The motor B may be driven by forcing a non-compressible liquid 17, preferably oil, to circulate through the 80 motor, the pressure being preferably supplied by steam.

A furnace 18, in the basement of the building, or other convenient location, generates steam which is conveyed from the boiler 19, 85 through a pressure pipe 20 leading upward through the floors 21, 22, 23 of the building to a pressure tank D which contains a non-compressible fluid, preferably water. The supply of steam under pressure to the tank 90 D is controlled by a valve E actuated by electromagnets 47 and 48, as will appear more fully hereinafter.

An oil pressure tank F communicates with the tank D through a connecting pipe 25 95 near the bottom of the tanks. The tank F is filled with oil and water, the water remaining in the lower part of the tank, owing to its specific gravity being greater than that of the oil. When the car A is at the lower 100 end of its shaft, the level of the water in the tank F is preferably just above the connecting pipe 25 to prevent oil from running into the water tank D and rising through the water. When steam pressure is admitted to 105 the tank D the water therein is forced through the pipe 25 into the tank F, the oil in the tank F being forced through a pressure pipe 26 leading through a valve chest G to the motor B through which the oil circulates, thereby driving the motor to lift the car. The oil is conveyed from the motor through an exhaust pipe 27 which also leads through the valve chest G to a reservoir 28. To lower the car, the supply of steam pressure is cut off, permitting the car to descend 110 by gravity, thereby rotating the motor B in the reverse direction which also reverses the circulation of the oil therein. In other words, as the car descends, the oil 17 runs 115 from the reservoir 28 through the motor, being pumped by the motor back into the oil tank F, the oil as it enters said tank forcing the water back into the tank D.

During the descent of the car, the valve E 125 is in position to cut off the steam pressure supply and open the tank D to an exhaust pipe 29 which leads to a condensing chamber 30. The latter contains a condensing coil 31, through which may circulate water 130

from a main 32. The coil 31 may serve as a heating coil from which water may be drawn through pipes 33 and 34 leading to the hot water taps 35 at the different floors of the building. These taps 35 as well as cold water taps 36 connected directly to the main 32, may be mounted at sinks 37.

- 5 The upper level of the water in the pressure tank D may be controlled by an overflow tank 38. A portion of the steam as it comes in contact with the water in the tank D is condensed and as the water reaches the level of a pipe 39 near the top of the tank it runs therethrough into an overflow tank 38. 10 The water as it rises in the overflow tank, lifts a float 40 and raises a valve 41, thereby opening the tank to a drain pipe 42 leading downward to a tank 43. The latter may be connected through a pipe 44 with the condensing chamber 30 to carry off the water that condenses in the latter. From the reservoir 43 the water may be pumped back into the steam boiler by a pump 45 driven by a motor 46. Thus very little water is wasted. 15 The valve mechanism for controlling the supply of steam to the pressure tank D will now be described:—

20 Referring particularly to Fig. 5, the electromagnets 47 and 48 for actuating the valve, may be conveniently mounted on the tank D. The magnet 47 comprises a core 47^a connected through a link 49 to an arm 50 secured to a rock shaft 51. The core 48^a of the magnet 48 is in like manner connected to said rock shaft. An arm 52 fixed to the rock shaft 51 is connected through a link 53 to a valve piston 54 which is vertically slideable in the cylindrical valve casing 55. The pressure and exhaust pipes 20 and 29 communicate with the valve chamber 56 respectively below and above the valve section 57. With the parts in their normal position of rest as shown in Fig. 5, which position is assumed when the car is at rest, communication 25 of the tank D with both the pressure and exhaust is cut off by the valve section 57 which blocks the pipe 58 leading from the valve chamber to the tank. If it is desired to supply pressure to the tank D, the electromagnet 47 is energized, causing its core 47^a to be drawn inward, thereby rocking the shaft 51 and swinging the arm 52 upward to the upper dotted line position, thereby lifting the valve section 57 into position to 30 open the port 58 and block the exhaust pipe 29. The pressure pipe 20 is thus placed in communication with the pipe 58, admitting steam under pressure to the tank D. In order to open the tank D to the exhaust pipe 29, the magnet 48 is energized so that its core 48^a is drawn downward, rocking the shaft 51 and carrying the arm 52 downward to the lower dotted line position, thus moving the valve section 57 down to block the 35 pressure pipe 20 and open the pipe 58 to the

exhaust pipe 29. When the operated magnet is again deenergized, a centering spring 60 operating on an arm 61 depending from the rock shaft 51, returns the parts to their normal position of rest. The valve mechanism 70 which directly controls the circulation of the oil through the motor and thereby regulates the speed of the motor will now be described.

This mechanism is shown in detail in Figs. 7, 8, 9 and 10. For the purpose of illustration the valve chest G is shown as containing four (4) vertically disposed valves 61, 62, 63, and 64. The oil for driving the motor flows from the pressure pipe 26 into a pressure chamber 65, (Fig. 10) and from thence 75 through one or more of the valve chambers 66 into a pressure chamber 67 from which leads a pressure pipe 68 to the motor. The return pipe 69 from the motor leads to a chamber 70 which may be connected through 80 one or more of the valve chambers 66 to a chamber 27^a which opens into the return pipe 27. It should be noted that the valves 61, 62, 63, and 64, which may be identical in construction, are in parallel relation, each 85 controlling a passage between the pressure chambers 65 and 67, and each also controlling a passage between the exhaust chambers 70 and 27^a.

90 The valves 61, 62, 63, and 64 are operated respectively by electromagnets 71, 72, 73 and 74. When the magnets are deenergized the valves move downward by gravity to their normal closed position shown in Fig. 10. With the valves in this position, it will be 95 seen that communication between the pressure pipes 65 and 67 is cut off, also between the exhaust chambers 70 and 27^a. Circulation of the oil through the motor is thus prevented. If an electromagnet, Fig. 10, 100 is energized, the connected valve 61 is drawn upward from the Fig. 10 position to the Fig. 8 position, so that communication is established from the pressure chamber 65 to the chamber 67, whereby a flow of oil to the motor is permitted. At the same time the exhaust chamber 70 is opened to the exhaust chamber 27^a, permitting the return flow of the oil from the motor. The speed of the motor is governed by the number of open 105 valves. The magnets 71 to 74 for operating the valves are controlled as hereinafter 110 pointed out.

115 The rotary motor B may be of the construction disclosed in the patent to A. Sundh, 1,159,613, or of other approved construction. For a detailed description of the motor, reference may be had to said patent. Briefly, the motor comprises a vertical casting 75 mounted on a bed plate 76, said casting containing a plurality of symmetrically disposed cylindrical bores 77, each of which may be lined with a bushing 78. Within each of said bores is located an oscillating disk 79. Each disk is provided with a cy- 120 125 130

lindrical bore 80 extending at right angles to the axis of the disk, within which is an oscillating trunk piston 81. The pistons 81 are all connected at their inner ends to a 5 crankpin 82, on the motor shaft 11.

A cover plate 83 of the motor (Fig. 3) is provided with two annular chambers 84 and 85 connected respectively with the pressure and exhaust pipes 68 and 69. The 10 pressure chamber 84 is in constant communication with a series of pressure chambers 86, and the exhaust chamber 85 is likewise in constant communication with the exhaust chambers 87, there being one chamber 86 15 and one chamber 87 for each disk 79. Each disk 79 is provided with a port or passage 88 which may be brought into communication with a pressure chamber 87, and a passage or port 89 which may be brought 20 into communication with an exhaust chamber 86. When a piston is at the outer limit of its movement (as the uppermost piston in Fig. 2,) both the ports 88 and 89 are closed.

Assuming the crank 82 to be rotating in a 25 counter clockwise direction Fig. 2, it will be seen that the pistons on the right hand side are being drawn inward and that the ports 89 provide an open passage from the pressure chamber 86 to the piston cylinders, so 30 that oil under pressure is admitted to the cylinders to drive them inward. It will also be seen that the exhaust ports 88 are closed. During the outward movement of the pistons, the pressure ports are closed and 35 the exhaust ports 88 are open. There is thus a continuous circulation of the oil through the motor while the latter is running. As the motor is run in the reverse direction while the car is going down, the circulation of the oil through the motor is 40 reversed. The terms pressure and exhaust have been applied for convenience to various chambers and pipes, but it will be understood that these are merely relative terms 45 and also that their use assumes that the motor is being driven in a certain direction.

The brake mechanism C comprises a pair of brake shoes 90 adapted to bear on a brake pulley 91 keyed to the shaft 11. The brake shoes are pivotally mounted on brake levers 92 connected by pivots 93 to a standard 94. Toggle links 95 connect the brake levers to a piston rod 96 and piston 97 which works in a cylinder 98. The brake shoes are normally applied by the power of a spring 99 which bears downwardly on the piston 97. The brake shoes are lifted by steam pressure admitted to the cylinder 98 beneath the piston, through a port 100 controlled by a 50 valve 101, said valve being actuated by an electromagnet 102. When the magnet 102 is energized and the valve 101 thereby lifted, steam pressure is admitted through a pipe 103, Fig. 1, through the port 100 and lifts 55 the piston 97 to release the brake shoes.

The various electromagnets are actuated from a controller in the car comprising a controlling lever 104. Current is supplied from any suitable source, through positive and negative mains 106 and 107 connected 70 to the controlling circuits through a switch 105. If the controlling lever is moved to the right from a central position, it establishes circuits through the magnets for causing the motor to drive the car upward. The lever 75 first makes connection with a contact bar 108 and thereby establishes a circuit for the electromagnet 47 which may be traced from the positive main 106 through conductor 109, switch lever 104, contact 108, conductor 80 110, magnet 47, conductor 111, brake controlling magnet 102, and conductor 112 to the negative main. The magnet 47 being energized lifts the valve 54 as already described to permit steam pressure to the tank 85 D. The brake controlling magnet 102 at the same time permits steam pressure to the cylinder 98 to release the brake.

The motor B is still locked against rotation on account of the bank of valves G 90 being closed and preventing the circulation of the oil through the motor, but the continued movement of the controller lever to the right imminently brings a contact 113 on said lever into engagement with a contact *a*, and then contacts *b*, and *c* and *d* in 95 succession thereby establishing circuits for the magnets 71, 72, 73 and 74 respectively. When 113 contacts with *a*, a circuit is completed through conductor 109, contacts 113, 100 *a*, 114, and magnet 71. The magnet 71 therefore lifts the valve 61 and permits a restricted flow of oil through the motor under the steam pressure transmitted through the water and oil tanks D and F. The motor is 105 thus started in a direction to lift the car but can only be run at a slow speed owing to the restriction of the oil through the ports of the valve 61.

As the magnets 72, 73, and 74 are successively energized when the contact 113 engages contacts *b*, *c*, *d*, the valves 62, 63, and 110 64 are successively opened permitting a correspondingly greater flow of oil to the motor, thereby increasing its speed. When 115 the controller lever is returned to central position the electromagnets controlled thereby are deenergized in the reverse order, permitting the valves to return to normal position. The supply of oil to the motor is thus 120 gradually cut off and then the supply of steam pressure to the tank D and to the brake cylinder 97, is also cut off causing the brake to be applied by its spring 96.

When the controller lever is thrown to the 125 left from central position, it first engages a contact 115 thereby establishing a circuit through conductor 109, lever 104, contact 115, conductor 116, electromagnet 48, brake controlling magnet 102, and conductor 112. 130

The magnet 48 moves the piston of the valve E downward, thereby opening the tank D to the exhaust pipe 29. The continued movement of the controller lever to the left 5 completes circuits for the magnets 71, 72, 73 and 74 through contacts a', b', c', d', said magnets thus being operated to open their valves 61, 62, 63, 64, whereby the oil is permitted to circulate through the motor. The 10 brake has now been lifted, and the car, due to its weight, starts downward. The motor being driven by the car, acts as a pump to draw the oil from the tank 28, and returns it to the oil tank F, the oil in the tank F in 15 turn forcing the water back into the tank D.

The speed of the car is controlled during both its ascent and descent, by the position of the controller lever which determines how many of the valves 61, 62, 63, and 64 shall 20 be open at any time.

Although for the purpose of illustration, I have shown the system arranged to show a single elevator car, it will be understood that where a bank of elevators is installed, 25 a common steam generating plant for all the elevators may be employed, and also a common discharge tank may be used for all the elevators.

It will be seen that the various valves for 30 controlling the steam and the circulation of the liquid for driving the motor are "balanced." That is, in any valve chamber, the upward and downward pressures of the fluid on the vertically movable valve therein, are 35 equal. The inner faces of the valve chambers are also provided with annular recesses 120 opposite their ports whereby lateral pressure on the valves is avoided.

By the terms hydraulic motor or hydraulic engine is meant a motor or engine 40 operable by the circulation therethrough of a liquid or non-compressible fluid such as oil or other lubricating liquid.

Variations may be resorted to without departing from the spirit and scope of my invention and portions of the invention may 45 be used without others.

What I claim is:—

1. In a hydro-steam elevator system, the 50 combination with a car and an engine to drive the car, means to supply steam under pressure providing driving power for the engine, and two columns of fluid, consisting respectively of a column of water and a column 55 of lubricating fluid, both interposed between the steam and the engine, said column of lubricating fluid communicating with the engine, and said water column interposed between the steam and lubricating fluid to 60 drive the latter through the engine.

2. In a hydro-steam elevator system, the 65 combination with a car and an engine to drive the car, means to supply steam pressure, a lubricating fluid actuated by the steam pressure and circulated through the

engine to drive it, and a water column interposed between the steam and said fluid.

3. In a hydro-steam elevator system, the combination of an elevator car, an engine at the upper end of the elevator shaft arranged 70 to drive and control the car, said engine having inlet and discharge ports, receptacles communicating respectively with the inlet and discharge ports, liquid for driving the motor, said engine operable by said liquid 75 circulating therethrough from one receptacle to the other, a steam generating plant, a riser through which steam is conveyed for applying pressure to the liquid in one receptacle to cause the liquid to drive the motor. 80

4. In a hydro-steam elevator system a steam generating plant, an elevator car, a hydraulic motor in an elevated position, arranged to drive the car, liquid to drive the motor, receptacles for said liquid adjacent 85 the upper end of the elevator shaft, a riser from the steam generator through which steam is conveyed upward to the liquid in one receptacle and by which the liquid is forced through the motor to the other receptacle and thereby caused to drive the motor, 90 and means to exhaust the steam.

5. In a hydro-steam elevator system, the combination with a car, of an engine operable to drive the car, said engine having an 95 inlet port and a discharge port, conduits communicating respectively with said ports for conveying a fluid to and from the engine, and valve mechanism comprising a series of valves each controlling a passage in 100 both said conduits, and means to operate said valves *seriatim*.

6. In a hydro-steam elevator system, the combination of a car, a motor operable by a fluid circulating therethrough to drive the 105 car, inlet and discharge ports for the motor, conduits leading from said inlet and discharge ports respectively for the passage of an operating fluid, valve mechanism controlling the flow of fluid through both said 110 conduits, means to supply steam under pressure for operating said fluid, an exhaust port for the steam, and valves controlling both the steam pressure and exhaust ports.

7. In a hydro-steam elevator system, the 115 combination with an elevator shaft, of an engine at the upper end of said shaft, said engine having a rotary drive shaft, an elevator car, a drum connected to the drive shaft, hoisting cables connecting the car 120 and drum, means to supply steam pressure, a lubricating fluid actuated by the steam pressure to drive the engine, and means co-operating with the engine to complete a circulating system for the fluid by which the 125 fluid is all retained at about the level of the upper end of the elevator shaft.

8. In a hydro-steam elevator system, a hydraulic engine having a rotary drive shaft, a car, means whereby the car is driven from 130

- 6 said shaft, steam actuated brake mechanism, valve mechanism to control the supply and exhaust steam to and from the brake mechanism, valve mechanism operable to control 5 the flow of liquid through the engine to thereby control the starting and stopping of the engine, a controlling lever, and electro-responsive means actuated thereby to concomitantly control said valve mechanisms.
- 10 9. In a hydro-steam elevator, the combination of a car, a motor to drive the car, the motor having inlet and exhaust ports, a non-compressible lubricating fluid by which the 15 motor is driven, a receptacle to contain said fluid and from which the latter is conveyed through said inlet port to the motor, means to supply steam pressure to the fluid in said receptacle, and a pressure transmitting medium through which the steam pressure is applied to said fluid and by which the steam is prevented from entering the receptacle, and a receptacle to which the fluid is conveyed from the motor through said exhaust 20 port.
- 25 10. In a hydro-steam elevator, the combination of a car, a hydraulic motor comprising a rotary element connected to drive the car, a non-compressible lubricating fluid, a pressure tank containing said fluid for operating said motor, means for supplying steam under pressure and transmitting said pressure to said non-compressible fluid and driving it through the motor to operate the 30 motor, said transmitting means comprising a liquid interposed between the steam and said lubricating fluid, and a receptacle separate from the pressure tank, containing said liquid.
- 35 40 11. In a hydro-steam elevator, the combination of a car, a counter-weight, a motor having an inlet and an outlet port and comprising a rotary drive shaft, a drum on said shaft suspending said car and counterweight, a non-compressible fluid for operating said 45 motor, an open tank communicating with the outlet port, a closed tank containing said fluid and communicating with the inlet port and means for supplying steam under pressure and transmitting said pressure to said non-compressible fluid in the closed tank and driving said fluid through the motor into the open tank and thereby operating the motor.
- 50 55 12. In a hydro-steam elevator, the combination of a hydraulic motor having a plurality of cylinders, pistons in said cylinders, a drive shaft connected with said pistons, a drum attached directly to said drive-shaft, a car and a counterweight, cables suspending said car and counterweight from the drum, a liquid for operating the pistons in the cylinders and causing the pistons to rotate the drum, and means for supplying 60 steam under pressure and transmitting said pressure to the liquid in the cylinders.
- 55 13. In a hydro-steam elevator, the combination of a car, a motor comprising a rotary element connected to drive the car, a non-compressible lubricating fluid for operating 70 said motor, a pressure tank containing said fluid, means for supplying steam under pressure, a compartment separate from said tank, and water in said compartment forming a medium for transmitting said pressure 75 to said non-compressible fluid.
14. In a hydro-steam elevator, the combination of a car, a motor comprising a rotary element connected to drive the car, a non-compressible lubricating fluid circulating 80 through the motor for operating it, means for supplying steam under pressure, and a water column between the said lubricating fluid and the steam, through which said pressure is transmitted to said lubricating 85 fluid.
15. In a hydro-steam elevator, the combination of a car, a counterweight, a motor for driving said car and counterweight, comprising a plurality of cylinders, pistons 90 working in said cylinders, a rotary element, a non-compressible lubricating fluid for operating the pistons in said cylinders, and causing the pistons to drive the rotary element, and means for confining steam under 95 pressure and transmitting said pressure to said non-compressible fluid in the cylinders, said transmitting means comprising a water column between said non-compressible lubricating fluid and the steam.
- 100 16. In a hydro-steam elevator, the combination of a car and a motor having a rotary drive shaft to drive the car, a non-compressible lubricating fluid for operating said motor, means for confining steam under 105 pressure to drive said fluid, a water column between said non-compressible fluid and the steam, and means to contain said non-compressible fluid arranged at a higher level than said water column.
- 110 17. In a hydro-steam elevator, the combination of a car, a rotary element for transmitting power for driving said car, a multiple-piston engine arranged to drive said rotary element, a non-compressible fluid for operating said engine, means to supply steam under pressure for keeping said non-compressible fluid under pressure and driving it through the engine to operate said engine, and a receptacle arranged to receive 115 the fluid discharged from the engine after driving it.
- 120 18. In a hydro-steam elevator, the combination of a rotary element, a car and counterweight suspended from said rotary element, a multiple piston engine for driving said rotary element in one direction to move the car in one direction, means to supply a 125

- non-compressible fluid to said engine, means to supply steam pressure for keeping said non-compressible fluid under pressure to operate the engine, said engine being driven in 5 the opposite direction independently of power supplied thereto by said fluids. 65
19. In a hydro-steam elevator, the combination of a rotary element, a car and a counterweight suspended from said element, a 10 motor comprising a rotary drive shaft connected directly to drive said element, cylinders extending radially from the axis of the drive shaft and pistons reciprocating in the cylinders, said element and shaft being rotatable by the weight of the car as the latter descends, and a non-compressible fluid actuated by steam pressure to drive said motor for raising the car, said fluid circulating through the motor while the car descends, 15 and means to control said circulation and thereby control the speed of motor and car as the car descends. 20
20. In a hydro-steam elevator, the combination of a rotary element, a car and counterweight suspended from said element, a motor comprising a rotary drive shaft connected to drive said element, said element and shaft being rotatable as the car descends, by a load including the car itself, and a non- 25 compressible lubricating fluid actuated by steam under pressure for driving said motor and thereby rotating said rotary element in the opposite direction and raising the car, and a water column interposed between said 30 non-compressible fluid and the steam. 35
21. In a hydro-steam elevator, the combination of a rotary element, a car and counterweight suspended from said element, a motor comprising a rotary drive shaft connected to drive said element, said element and shaft being rotatable as the car descends, by a load including the car itself, and a non-compressible lubricating fluid actuated by steam under pressure for circulating 40 said fluid through the motor and thereby driving said motor and rotating said rotary element in the opposite direction and raising the car, and tanks into which the liquid is conveyed from the motor respectively during 45 the ascent and descent of the car, and means to control the rotary element from the car. 50
22. In an elevator, the combination of a rotary element, a car and counterweight suspended from said element, a motor to drive said element, said rotary element being rotatable as the car descends by a load including the car itself, and a non-compressible lubricating fluid actuated by steam under pressure 55 for circulating said fluid through the motor and thereby driving the motor in the opposite direction and raising the car, tanks into which the liquid is conveyed from the motor respectively during the ascent and de- 60
- scent of the car, valve mechanism for controlling said non-compressible lubricating fluid and the steam pressure, and manually operative means in the car for controlling said valve mechanism. 65
23. In an elevator, the combination of a rotary element, a car and counterweight suspended therefrom, a motor having a drive shaft connected to said element, lubricating liquid, means to supply steam under pressure to drive said liquid and cause the latter to drive the motor, valve mechanism controlling the supply of steam, separate valve mechanism controlling the circulation of said liquid and thereby controlling the speed of the motor, and electro-responsive means for controlling said valve mechanism. 70
24. In an elevator, the combination of a rotary element, a car and a counterweight suspended therefrom, a motor having a drive shaft connected to said element, and radially reciprocating pistons, means to supply steam under pressure, a fluid actuated by said pressure and operable to drive said motor and cause it to lift the car, said fluid controlling the motor during the descent of the car, valve mechanism arranged to concomitantly control said fluid and steam, and means in the elevator car for controlling said valve mechanism. 75
25. In an elevator, the combination of a rotary element, a car and counterweight suspended therefrom, a motor having a drive shaft connected to said element, said motor operative to lift the car and concomitantly lower the counterweight, means to supply steam under pressure, oil driven by the steam to actuate said motor in a direction to lift the car and lower the counterweight, a water column interposed between the steam and oil and means to control the circulation of oil and thereby control the rotation of the motor during the descent of the car and the ascent of the counterweight. 80
26. In an elevator, the combination of a rotary element, an engine connected to drive and control said element, a car and counterweight suspended from said element, ports for said engine, a pressure reservoir connected with one port, a liquid in said reservoir, an open tank connected with the other port, means to supply steam under pressure to said liquid for forcing the liquid through the engine to thereby drive the engine, the liquid being discharged from the engine into the open tank, the engine being operative when driven by said liquid, to rotate the rotary element in a direction to raise the car and lower the counterweight. 85
27. In an elevator, the combination of a rotary element, an engine connected to drive and control said element, a car and a counterweight suspended from said element, ports for said engine, a pressure reservoir 90
- 100
- 105
- 110
- 115
- 120
- 125

connected with one port, a liquid in said reservoir, an open tank connected with the other port, means to supply steam under pressure to said liquid for forcing the liquid 5 through the engine to thereby drive the engine, the liquid being discharged from the engine into the open tank, the engine being operative when driven by said liquid, to rotate the rotary element in a direction to raise 10 the car and lower the counterweight, means to cut off the supply of steam from said liquid, and means to connect the pressure tank with an exhaust, thereby permitting the rotary element to be driven by a load including 15 the elevator car and drive the engine, and cause the latter to draw the fluid from the open tank and return it into the pressure reservoir as the car descends.

28. In an elevator, the combination of an 20 engine comprising a plurality of cylinders and pistons working in the cylinders, a shaft connected with said pistons, a traction sheave on said shaft, cables running on said sheave, a car and a counterweight suspended 25 by the cables, a liquid under pressure for actuating said pistons, means to supply steam under pressure for applying pressure to said liquid, and means to control said liquid and steam pressure, and thereby cause 30 the elevator and counterweight to be raised and lowered by said engine.

29. In an elevator, the combination of a multiple cylinder engine comprising pistons reciprocating in the cylinders, an engine 35 shaft connected to said pistons, a traction sheave on said shaft, an elevator car and counterweight suspended from said traction sheave and driven thereby, a liquid to drive said engine, a pressure tank containing said 40 liquid, means to supply steam under pressure and apply said pressure to said liquid in the tank and cause it to circulate through the engine and drive the engine, and valve mechanism interposed between the engine 45 and said tank and controlling the rate of flow of the liquid to the engine, thereby controlling the speed of the engine.

30. In an elevator, the combination of a multiple cylinder engine comprising pistons 50 reciprocating in the cylinders, an engine shaft connected to said pistons, a traction sheave on said shaft, an elevator car and counterweight suspended from said traction sheave and driven thereby, a liquid to drive said engine, ports to admit and discharge 55 said liquid to and from said cylinders, a pressure tank connected with one of said ports, an open tank connected with the other port, means to supply steam under pressure to 60 said pressure tank to apply pressure to said liquid, and means to control the admission of steam pressure to the liquid and the circulation of the liquid for actuating the engine to raise the elevator car and to control the descent of the car.

31. In a hydro-steam elevator, the combination of a car, a motor having a rotary drive shaft connected to drive the car, a liquid for operating said motor, means for supplying steam under pressure for keeping 70 said liquid under pressure to operate said motor, valve mechanism controlling the flow of said liquid to the motor to thereby control the speed of the motor, separate valve mechanism controlling the supply of 75 steam pressure to said liquid, and electromagnetic means to actuate the valve mechanisms.

32. In a hydro-steam elevator, the combination of a car, a motor having a rotary 80 drive shaft connected to drive the car, a liquid for operating said motor, means for supplying steam under pressure for keeping 85 said liquid under pressure to operate said motor, valve mechanism controlling the flow of said liquid to the motor to thereby control the speed of the motor, separate valve mechanism controlling the supply of steam pressure to said liquid, and electromagnetic 90 means to actuate the valve mechanism, and a manually operated switch in the elevator car for controlling said electromagnetic means.

33. In an elevator, the combination of a car, an oil driven motor connected to drive 95 the car, means to contain oil for driving the motor, means to supply steam under pressure to apply pressure to the oil, and a pressure transmitting medium consisting of a liquid heavier than oil interposed between the steam and the oil.

34. In an elevator, the combination of a car, an oil driven motor connected to drive the car, means to contain oil for driving the motor, means to supply steam under pressure to apply pressure to the oil, and a liquid 105 heavier than the oil arranged to prevent the steam from coming in direct contact with the oil.

35. In an elevator system, the combination of a multiple cylinder engine, a shaft for said engine, said engine comprising pistons in said cylinders and connected to said shaft, inlet and outlet ports for said cylinders, and a fluid adapted to be circulated through said cylinders to drive the engine in one direction and to control the running of the engine in the other direction, said fluid being actuated by steam pressure while driving the engine, a traction sheave 110 on the engine shaft, and an elevator car and a counterweight suspended from said traction sheave and operated thereby.

36. In an elevator system, the combination of an engine, a traction sheave operated 115 thereby, an elevator car and a counterweight suspended from said sheave, a steam generating plant, a pressure tank for the engine, containing oil adapted to circulate through and drive the engine, a pressure tank con- 120 130

taining water communicating with the oil tank, means for conveying steam from the generating plant to said water pressure tank, and valve mechanism for controlling the 5 supply of steam and the circulation of said oil.

37. In an elevator system, the combination of a multiple cylinder engine comprising pistons in the cylinders, a shaft to 10 which the pistons are connected, a traction sheave on said shaft, an elevator car and counterweight suspended from said sheave, a liquid operable under pressure to actuate said engine and drive said car and counter- 15 weight, a tank containing said liquid and communicating with the engine, and means to supply steam under pressure to said tank, an exhaust tank into which the liquid is exhausted from the engine and from which 20 the engine is operable to pump the liquid back into the pressure tank, and means to regulate the return flow of liquid and thereby control the speed of the motor.

38. In an elevator, the combination of a 25 car, a counterweight, a traction sheave, an engine for driving said sheave, said engine having inlet and discharge ports, containers, oil therein, said containers opening respectively to said inlet and exhaust ports, means 30 to supply steam under pressure for actuating said oil and causing it to drive the engine and rotate the traction sheave, and thereby drive the car and counterweight.

39. In an elevator, the combination of a 35 car, a counterweight, a traction sheave, an engine for driving said sheave, said engine having inlet and discharge ports, containers, oil therein, said containers opening respectively to said inlet and discharge port, 40 means to supply steam under pressure, and transmit said pressure to the oil in one of said containers, and thereby cause the oil to circulate through the engine and drive it in a direction to lift the car.

40. In an elevator, the combination of an 45 elevator car, a counterweight, a traction sheave from which said car and counterweight are suspended, an engine for driving said traction sheave, ports on said engine 50 forming inlet and discharge, and means to contain a lubricating fluid connected to each of said ports, steam pressure for obtaining pressure on the fluid in one of said means, and thereby circulating the fluid through 55 the engine and driving the engine and cause the elevator to be raised, means to cut off said steam pressure, and means to connect said last mentioned container with an exhaust to relieve the steam pressure from the 60 oil lubricating fluid and thereby cause the elevator car to descend.

41. In an elevator, the combination of a 65 traction sheave, a car and counterweight suspended from said sheave, an engine for driving said sheave, said engine including

a plurality of cylinders, two chambers, and ports individual to said cylinders and connecting each cylinder to both of said chambers, containers for oil connected respectively to said chambers, means for supplying 70 steam under pressure for controlling said oil and causing it to drive the engine in one direction, and means to cut off said steam pressure and permit the engine to be driven in the opposite direction by a load including 75 the elevator car.

42. In an elevator, the combination of a car, a counterweight, a traction sheave suspending said car and counterweight, an engine for driving said sheave, said engine 80 having pressure and discharge ports, two pressure tanks connected in series with the pressure port, and a discharge tank communicating with the discharge port, oil in one of said pressure tanks, the other containing 85 water, and means for conducting steam under pressure to the water pressure tank.

43. In a hydro-steam elevator system, the combination of a traction sheave, a fluid motor for rotating said sheave, a car and a 90 counterweight suspended from said sheave and operated thereby, means to lock the fluid in the motor and thereby control the motor, a brake for said motor, means to supply steam pressure for operating the brake, a 95 valve to control said supply, and electro-responsive means to control the valve.

44. In a hydro-steam traction elevator system, the combination of a fluid engine, a traction sheave driven thereby, a car and 100 a counterweight suspended from said sheave, a fluid, means to supply steam under pressure to said fluid for operating said engine in one direction, the engine being driven in the opposite direction by a load 105 including the car, means to break the engine by locking the fluid therein and a brake operated by steam pressure.

45. In a hydro-steam elevator system, the combination of a traction sheave, a fluid 110 motor for operating said sheave, means for locking the fluid in the motor and thereby controlling the motor, a car and a counterweight suspended from said sheave and operated thereby, a steam operated brake 115 for said motor, means to supply steam for operating the brake, valve mechanism controlling the supply of steam to the brake, and electro-responsive means controlled from the car for controlling said valve 120 mechanism.

46. In a hydro-steam elevator system, the combination of a fluid motor and a traction sheave connected thereto and adapted to be rotated thereby, a car and a counterweight 125 suspended from said traction sheave, valves arranged to lock the fluid in the motor and thereby control the motor, a steam operated brake for said motor, means to supply steam pressure to operate the brake, and electro- 130

- responsive means to concomitantly control said steam pressure and said valves at will from the elevator car.
47. In a hydro-steam elevator system, the combination of a traction sheave, a fluid motor for rotating said sheave, motor-controlling valves to lock fluid in the motor, a car and a counterweight suspended from said sheave and operated thereby, a brake for said motor, a spring for applying the brake while the motor is at rest, means operated by steam for releasing the brake, and electro-magnetically operated valve mechanism to control the supply of steam to said releasing means, and thereby control the brake.
48. In a hydro-steam elevator system, the combination of a traction sheave, a fluid motor for rotating said sheave, a car and a counterweight suspended from said sheave and operated thereby, a brake for said sheave means to operate said brake by steam, and an electro-responsive device for controlling said brake.
49. In a hydro-steam elevator system, the combination of a traction sheave, a fluid motor for rotating said sheave, a car and a counterweight suspended from said sheave and operated thereby, a brake for said motor, means to operate said brake by a fluid, an electro-responsive device for controlling said fluid, and a manually operated switch in the car for controlling said electro-responsive device.
50. In a hydro-steam elevator system, the combination of a traction sheave, a fluid motor for rotating said sheave, a car and a counterweight suspended from said sheave and operated thereby, a brake for said motor, brake applying means including a cylinder, and a piston in said cylinder, means to supply fluid under pressure to the cylinder for operating said piston, a valve for controlling said fluid, an electro-responsive device for operating said valve, and a manually operated circuit closer in circuit with said electro-responsive device for controlling it.
51. In a hydro-steam elevator system, the combination of a traction sheave, a fluid engine for rotating said sheave, a car and a counterweight suspended from said sheave and operated thereby, a lubricating fluid for driving the engine, ports for said fluid to enter the engine and discharge therefrom, means to supply steam under pressure for actuating said fluid, a brake, and a controller operable to control said fluid, said steam, and said brake.
52. In a hydro-steam elevator system, the combination of a traction sheave, a fluid motor for rotating said sheave, a car and a counterweight suspended from said sheave and operated thereby, a brake for said motor, oil to drive the motor, means to supply steam under pressure for circulating said oil and thereby driving the motor in one direction, means to control said steam and said oil, mechanism actuated by steam pressure for operating the brake, and means for controlling the steam pressure to the brake operating mechanism in conjunction with the first mentioned controlling means.
53. In a hydro-steam elevator system, the combination of an elevator car and counterweight, an oil engine, a traction sheave rotatable thereby and suspending said car and counterweight, oil to drive the engine, means to supply steam under pressure for circulating the oil to thereby drive the engine, a plurality of valves for controlling the circulation of the oil, a valve controlling the steam, electromagnets to operate said valves, and a manually operated electric switch in the car to effect the operation of the electromagnets and thereby cause a concomitant operation of said valves.
54. In a hydro-steam elevator, the combination with a car and a motor to drive the car, said motor operable by the circulation of oil therethrough, of an oil pressure tank, a water pressure tank, a pressure pipe leading from the upper portion of the oil tank to the motor, a pipe connecting said tanks and opening into the tanks near the bottoms thereof, and a steam pipe opening into the water tank at the upper portion thereof whereby steam under pressure admitted through the steam pipe to water in the water tank may force the water through said connecting pipe into the oil tank and force oil from the oil tank through said pressure pipe to the motor and thereby drive the motor.
55. In a hydro-steam elevator, the combination with a car and a motor to drive the car, said motor operable by the circulation of oil therethrough, of an oil pressure tank, a water pressure tank, a pressure pipe leading from the upper portion of the oil tank to the motor, a pipe connecting said tanks and opening into the tanks near the bottom thereof, and a steam pipe opening into the water tank at the upper portion thereof whereby steam under pressure admitted through the steam pipe to water in the water tank may force the water through said connecting pipe into the oil tank and force oil from the oil tank through said pressure pipe to the motor and thereby drive the motor in one direction, a reservoir for the oil discharged from the motor, and a discharge pipe leading from the motor to said reservoir, the motor operable when running in the reverse direction to return the oil and water to their pressure tanks.
56. In a hydro-steam elevator system, the combination of a car, a motor to drive the car, said motor operable by circulation of oil therethrough, the motor having a sub-

stantially constant oil capacity so that the volume of oil therein remains substantially constant throughout its run, an oil pressure tank containing oil to drive the motor, means for conducting the oil from said tank to the motor, said tank being of a capacity to contain oil sufficient to drive the motor during a full run of the car from its lowest to its highest position, and a receptacle into which the oil is discharged during the run of the motor.

57. In a hydro-steam elevator, the combination of a car, a motor to drive the car, said motor operable by the circulation therethrough of oil under pressure, an oil pressure tank, a water pressure tank, said tanks being substantially on a level, a pipe connecting said tanks near their lower ends, the oil tank arranged to contain water in the bottom thereof, the level of the water being above said connecting pipe when the car is at the bottom of its run, said water in the oil tank supporting oil thereon, the oil tank being of sufficient capacity for the oil therein 20 to run the motor and lift the car from the bottom to the top of its run, and means to supply steam under pressure to the water tank and force the water therein through said connecting pipe into the oil tank and thereby drive the oil through the motor for driving the latter.

58. In an elevator, the combination of a car, a motor connected to drive the car, said motor operable by a liquid forced to circulate therethrough, a valve mechanism controlling the circulation of said liquid and comprising a plurality of valves in parallel relation in the circulating system, means to supply steam under pressure to apply during driving pressure to said liquid, a valve mechanism controlling the supply of steam, and valve controlling means to operate said valve mechanism in succession and arranged to open said parallel valves *seriatim*.

59. In an elevator, the combination of a car, a motor connected to drive the car, said motor operable by a liquid forced to circulate therethrough, valve mechanism controlling the circulation of said liquid and comprising a plurality of valves in parallel relation in the circulating system, each of said valves controlling ports through which the liquid is conducted to the motor, and separate ports through which the liquid is conducted from the motor, each valve permitting a restricted flow toward and from the motor, and valve controlling mechanism for opening any desired number of the valves to thereby control the speed of the motor.

60. In an elevator, the combination with a car, of a motor connected to drive the car, said motor operable by a liquid circulating therethrough, means forming with the motor, a circulating system for the liquid, valves in said system externally of the

motor and controlling the circulation of liquid through the motor, means to supply steam pressure to the liquid, a steam valve normally closed to cut off the supply of steam pressure while the motor is at rest, and a controller operable first to open the steam valve and then said first mentioned valves, whereby the steam pressure is applied to the liquid before the latter is permitted to circulate through the motor.

70

75

61. In an elevator, the combination with a car, of a motor connected to drive the car, said motor operable by a liquid circulating therethrough, means forming with the motor, a circulating system for the liquid, valves in said system externally of the motor and controlling the circulation of liquid through the motor, means to supply steam pressure to the liquid, a steam valve normally closed to cut off the supply of steam pressure while the motor is at rest, electromagnets for operating the valves, and a controller operative when moved from a normal position of rest, first to operate the magnet for the steam valve to admit pressure to the liquid, and then to operate the first mentioned valves successively to gradually open the circulating system.

80

85

90

62. In an elevator, the combination of a car, a motor connected to drive the car, an oil pressure tank to contain oil to drive the motor, a water pressure tank to contain water, said tanks being in communication to permit the water to displace the oil and drive the oil through the motor, means to supply steam under pressure to the water in the tank, an overflow pipe leading from the water tank, a trap to receive the overflow, and means operable automatically to discharge the water from said trap.

95

100

105

63. In an elevator, the combination of a car, a motor connected to drive the car, a lubricating fluid to drive the motor, a pressure tank containing said fluid, a water tank communicating with said pressure tank, means to supply steam under pressure to said water tank, whereby the water under said pressure may cause the lubricating fluid to drive the motor, an overflow chamber communicating with said water tank, a valve in said chamber, and a float arranged to operate said valve to discharge the water from said chamber.

110

115

64. In an elevator, the combination of a car, a motor connected to drive the car, said motor being operable by a liquid under pressure, means to supply steam under pressure to the liquid, a valve controlling the supply of steam to the liquid, a brake for the motor operable by steam under pressure, means for conducting steam to the brake independently of said valve, and a valve controlling the supply of steam to the brake, and valve mechanism controlling the circulation of liquid through the motor and operable to

120

125

130

lock the liquid in the motor thereby providing an additional brake for the motor.

65. In a hydro-steam elevator, the combination with a car, of a hydraulic motor having a rotary drive shaft, a drum and cables forming a driving connection between the motor and car, a non-compressible lubricating fluid to drive the motor, means to supply steam to apply pressure to said fluid, and a water column forming a pressure transmitting medium interposed between the steam and said fluid.

66. In a hydro-steam elevator, the combination with a car, of an overhead engine having a drive shaft connected to drive the car, liquid operable by circulation through the engine to drive it, means forming with the engine an overhead circulating system for said liquid, a steam generating plant, and a riser through which steam is conveyed from said plant upward through the building to supply pressure to said liquid and thereby cause it to drive the engine.

67. In an elevator system, the combination of a hydraulic motor having a rotatable shaft, a drum rotated by said shaft, a car, a counterweight, cables connecting said car and counterweight and suspending them from said drum, a steam generating plant, a riser from said steam generating plant to the engine, a fluid reservoir connected with said riser, and also connected with an inlet port of the engine, and a receiving reservoir connected with a discharge port of the engine, and means to control the fluid and the steam, and cause said fluid to be driven from the fluid reservoir through the engine to the receiving reservoir and thereby rotate the engine.

68. In an elevator system, the combination of a car, a hydraulic motor connected to drive the car, a fluid actuated by steam pressure to circulate through said motor and thereby drive it to lift the car, said car operable to drive the motor in the reverse direction and reverse the circulation of the fluid therethrough, two receptacles for said fluid, one receptacle arranged to receive the fluid from the motor when the car is driven by the steam pressure actuating the fluid, the other receptacle arranged to receive the fluid when the motor is driven by the car.

69. In an elevator system, the combination of a car, a hydraulic motor for driving said car, means suspending said car from said motor, fluid actuated by steam pressure to circulate through said motor and thereby drive it, two receptacles for said fluid, one receptacle arranged to receive the fluid discharged from the motor while the fluid is being actuated by steam pressure in the other reservoir, and is driving the motor.

70. In an elevator system, the combination with a car and counterweight, of a hydraulic motor for driving said car and coun-

terweight, a drum connected with said motor, cables suspending the car and counterweight from said drum, fluid actuated by steam pressure for driving said motor, two receptacles for said fluid, one receptacle arranged to receive the fluid as it is discharged from the motor while the fluid is being actuated to drive the motor by steam pressure applied in the other receptacle.

71. In an elevator system, the combination of an elevator car, a hydraulic motor having a rotatable shaft, a drum driven by said shaft, cables connecting the car with said drum, fluid actuated by steam pressure and thereby forced through the motor to drive the same, and a receptacle into which the fluid is discharged from the motor while the latter is being driven by said pressure.

72. In an elevator system, the combination of an elevator car, a hydraulic motor for driving said car, means for suspending said elevator car from said motor, a fluid actuated by steam pressure and thereby forced through the motor to drive it and lift the car, means to relieve the fluid from the steam pressure and cause the hydraulic motor to be driven by the car, and two receptacles for the fluid, namely one receptacle from which the fluid is forced through the engine by said steam pressure as the car ascends, the other receptacle arranged to receive the fluid as it is discharged from the engine during the ascent of the car.

73. In an elevator system, the combination of a car, a hydraulic motor for driving the car, means for suspending the car from the motor, a fluid actuated by steam pressure and thereby forced through the motor to drive it and lift the car, means to relieve the fluid from the steam pressure and cause the car to descend and drive the motor, and two receptacles for the fluid, the fluid being received by the motor from one receptacle and conveyed through the motor and delivered to the other receptacle during the descent of the car.

74. In an elevator system, the combination of an elevator car, a counterweight, a hydraulic motor having a rotatable shaft, a drum driven by said shaft, cables suspending said elevator car and counterweight from said drum, a fluid for driving the engine, means to supply steam pressure to said fluid and force it through the engine to drive the engine and lift the car, a receptacle to which the fluid is delivered as the car rises, said liquid being returned through the engine as the car descends by its weight, a receptacle to which the fluid is delivered from the motor as the car descends, and means to control the flow of fluid through the motor.

75. In an elevator system, the combination of a car, a counterweight, a hydraulic engine, a liquid for driving said engine, said engine having ports through each of

which the liquid flows to and from the engine alternately as the engine is operated in opposite directions, cables connecting the car and counterweight and suspended from

- 5 the engine, and a valve system comprising valves controlling said ports and having a normal rest position in which they cut off the flow of liquid at both ports whereby the fluid is controlled and locked in the engine
 10 between the ports, thereby holding the engine at rest.

76. In a hydro-steam elevator, the combination of an elevator car, a hydraulic motor, a rotatable drum connected to and driven by said motor, ropes suspending the car from said drum, said engine having inlet and discharge ports, valves at said ports, and valve controlling mechanism for simultaneously closing the valves at both said

20 ports and retaining them in closed position.

77. In a hydro-steam elevator system, the combination of a car, a counterweight, a hydraulic motor, fluid to drive the motor, a rotatable drum connected to and driven by
 25 the motor, ropes suspending the car and counterweight from the drum, said motor having inlet and discharge openings for the fluid, valves at said openings, and means for simultaneously actuating said valves to
 30 control the flow of fluid through said openings, thereby controlling the starting, running and stopping of the motor, said valves having a normal position of rest in which they close said openings and thereby lock
 35 the motor.

78. In a hydro-steam elevator system, the combination of a car, a counterweight, a hydraulic motor, fluid to drive the motor, a rotatable drum connected to and driven by
 40 the motor, ropes suspending the car and counterweight from the drum, said motor having inlet and discharge openings for the fluid, valves at said openings, and means for simultaneously actuating said valves to
 45 control the flow of fluid through said openings, thereby controlling the starting, running and stopping of the motor, said valves having a normal position of rest in which they close said openings and thereby lock the
 50 motor, said controlling means being located at the car and manually operable at will.

79. In a hydro-steam elevator system, the combination of a car, a counterweight, a hydraulic motor, fluid to drive the motor, a rotatable drum connected to and driven by
 55 the motor, ropes suspending the car and counterweight from the drum, said motor having inlet and discharge openings for the fluid, valves at said openings, means for
 60 simultaneously actuating said valves to control the flow of fluid through said openings, thereby controlling the starting, running and stopping of the motor, said valves having normal rest positions in which they
 65 close said openings and thereby lock the

motor, an electric control system controlling said valve actuating means, said system comprising a controller operable at will from the elevator car.

80. In a hydro-steam elevator system, the combination of a car, a counterweight, a hydraulic motor, a rotatable drum connected to and driven by the motor, ropes suspending the car and counterweight from the drum, a fluid for operating the motor, 70 and means to supply pressure for actuating the fluid, the motor having inlet and discharge ports for the fluid, a system of valve control for simultaneously controlling the fluid at said ports, and a valve controlling 75 system for controlling the steam.

81. In a hydro-steam elevator system, the combination of a car, a counterweight, a hydraulic motor, a rotatable drum connected to and driven by the motor, ropes 80 suspending the car and counterweight from the drum, a fluid for operating the motor, means to supply pressure for actuating the fluid, the motor having inlet and discharge ports for the fluid, a system of valve control for simultaneously controlling the fluid at said ports, a valve controlling system arranged to control the steam, and means to simultaneously actuate the valves of both
 90 said controlling systems. 95

82. In a hydro-steam elevator system, the combination of a car, a counterweight, a hydraulic motor, a drum connected to and driven by said motor, ropes suspending the car and counterweight from the drum, a 100 fluid for operating the motor, means to supply steam pressure for actuating said fluid to drive the motor in one direction, means to relieve the fluid from the steam pressure and cause the motor to be driven in the opposite direction by the weight of the car, said engine having inlet and discharge ports for the passage of said fluid, and a valve-controlling system for simultaneously controlling the fluid at both said ports for 105 starting the motor, for driving the motor in both directions, and for stopping the motor.

83. In a hydro-steam elevator system, the combination of a car, a counterweight, a 115 hydraulic engine, a drum driven thereby, ropes suspending the car and counterweight from said drum, a hatchway having guides for the car and counterweight, the engine being located in an elevated position relatively to the car and counterweight, a steam generating plant in the basement, a fluid for operating the engine, a riser for conveying the steam under pressure from said plant to the engine, the steam being operable to drive 120 said fluid through the engine to operate it, and means to control the flow of said fluid and the supply of steam pressure thereto.

84. In an elevator system, the combination of a car, a counterweight, a hydraulic 130

motor, a rotatable drum connected to be driven by the motor, ropes suspending the car and counterweight from the drum, fluid for operating the motor, and means to supply pressure for actuating the fluid, the motor having inlet and discharge ports for the fluid, and valve mechanism for opening said ports in running the elevator, and for closing both said ports and holding them closed for stopping the elevator and holding it stationary.

85. In an elevator system, the combination of a car, a counterweight, a hydraulic motor, a rotatable drum driven by said motor, ropes suspending the car and counterweight from the drum, fluid for operating the motor, and means to supply pressure for actuating the fluid, the motor having inlet and discharge ports for the fluid, and valve mechanism for simultaneously opening said ports gradually during the acceleration of the motor for controlling the acceleration of the car.

86. In an elevator system, the combination of a car, a counterweight, a hydraulic motor, a rotatable drum driven by the motor, ropes suspending the car and counter-

weight from the drum, fluid for operating the motor, and means to supply pressure for actuating the fluid, the motor having inlet and discharge ports for the fluid, and valve mechanism for simultaneously closing said ports gradually during the stopping of the motor for obtaining a smooth slowing down and stopping of the elevator.

87. In an elevator system, the combination of a car, a counterweight, a hydraulic motor, a rotatable drum connected to be driven by the motor, ropes suspending the car and counterweight from the drum, fluid for operating the motor, and means to supply pressure for actuating the fluid, the motor having inlet and discharge ports for the fluid, and valve mechanism for simultaneously opening or closing said ports different extents while the motor is running to thereby control the speed of the car, and also control the stopping of the car entirely by the locking of the fluid in the motor.

Signed at Chicago, in the county of Cook 50 and State of Illinois this 26th day of April A. D. 1916.

JOHN J. SPROUL.
